UNITED STATES PATENT OFFICE.

WILLIAM THOMPSON POOL, OF COLUMBUS, GEORGIA.

COMBINED COFFER-DAM AND CAISSON.

SPECIFICATION forming part of Letters Patent No. 728,497, dated May 19, 1903.

Application filed September 16, 1902. Serial No. 123,648. (No model.)

To all whom it may concern:

Be it known that I, WILLIAM THOMPSON POOL, a citizen of the United States, residing at Columbus, in the county of Muscogee and State of Georgia, have invented a new and useful Combined Coffer-Dam and Caisson, of which the following is a specification.

This invention relates to a combined coffer-dam and caisson.

The invention has for its object to produce a device of this character which will be strong and durable, efficient in operation, and one which is admirably adapted for all classes of submarine work and for the laying of foundations or the like which necessitate working below water.

With the above and other objects in view, as will appear as the nature of the invention is better understood, the same consists in the novel construction and combination of parts of a combined coffer-dam and caisson, as will be hereinafter fully described and claimed.

In the accompanying drawings, forming a part of this specification, and in which like numerals of reference indicate corresponding parts, there are illustrated two forms of embodiment of the invention, each capable of carrying the same into practical operation, it being understood that the elements therein exhibited may be varied or changed as to shape, proportion, and exact manner of assemblage without departing from the spirit thereof, and in these drawings—

Figure 1 is a view in sectional elevation of a form of structure embodying the essential features of this invention. Fig. 2 is a sectional view taken at right angles to the plane of that on which Fig. 1 is taken. Fig. 3 is a view in horizontal section. Fig. 4 is a fragmentary detail view showing one manner of staying or bracing the caisson.

Referring to the drawings and to Figs. 1, 2, 3, and 4, there is illustrated a form of combined coffer-dam and caisson to be used in building submarine structures. The structure is truncated pyramidal as viewed in side elevation and rectangular as viewed in end elevation. The pitch or incline of the walls of the structure may be greater or less than that shown, the angular disposition of the parts being determined by the work to be done. The casing as a whole is composed of

inner and outer sheathing 1 and 2, of boards, spaced apart by vertical timbers or scantlings 3, (shown in Fig. 3,) the space between the sheathings being packed with a suitable filling of cement 4, thus to render the structure waterproof. The seams between the sheathings may be calked or otherwise treated to render them proof against entrance of water. The structure is braced internally and externally by cross-timbers 5 and 6, the whole being tied firmly together by tie-rods 7, carrying turnbuckles 8, the outer ends of the rods by preference being passed through brace-beams 9, bearing against the outer sides of the structure.

The upper portion of the structure is divided into two chambers by a flooring 10 and a partition 11, and its upper end is closed by a roof or cover 12, carrying in this instance two downward-opening doors 13, provided with bull's-eyes 14, the doors 13 being constructed to fit their openings with sufficient closeness to preclude entrance of water. While but two doors 13 are herein shown, it is to be understood that this number may be increased, if found necessary or desirable. Communication between the two chambers 15 and 16 is established through a door 17, by preference hinged at its upper edge, so that it will always by gravity remain closed. The floor 10 in one of the compartments is provided with a bull's-eye 18 and in the other compartment with a downward-opening door 19, also provided with a bull's-eye 20, the bull's-eyes being provided to furnish requisite light in clear weather to enable the workmen to see with sufficient clearness to carry on their labor. Connected in this instance with the floor of the compartment 16 is a ladder 21, which extends downwardly to the bottom of the casing and is by preference a rope ladder.

In order to adapt the casing to rest upon uneven bottoms and at the same time be capable of precluding entrance of water under the edges thereof, its lower inner portion has connected with it a flexible shield or border 22, preferably of rubber, tarpaulin, or any other suitable waterproof material, which projects inward any desired distance and is adapted to be weighted down by stones or the like, as shown in Figs. 1 and 2, thereby in a positive and simple manner cutting off en-

trance of water to the casing beneath the edges of the latter. The shield or border may be raised when it is desired to work under the edges of the casing.

- 5 Air is supplied from a suitable compressor through a pipe 23, discharging, preferably, near the bottom of the casing, and its quantity may be easily regulated by a valve 24. The upper portion or roof of the casing has 10 safety-valves 24^a associated with it to permit escape of air at the top in case it cannot escape at the bottom, thereby avoiding excessive pressure within the casing.

In order to provide for the discharge without the casing of debris removed by the workman, a trough or holder 32 is provided, with which connects a spout 33, leading without the casing, the spout having a valve 34 associated with it which normally closes entrance 20 to water and also prevents escape of air. Communicating with the trough is a pipe 35, which leads to a source of air under pressure or to a compressor. In discharging debris from the casing the workman dumps it in the 25 trough 32 and opens a valve 36 on the pipe 35, whereupon compressed air immediately blows the debris out. When all is discharged, the valve 34 is closed by back-water pressure.

The form of casing just described is adapted for use in connection with the laying of 30 submarine tubes or cables, in building foundations, or erecting piers, and, if preferred, it may be employed as a sheathing, say, to a pier, the whole interior being filled with concrete or other material to constitute the pier, and the structure will add additional strength 35 to it. Of course under these conditions all internal mechanism would be removed, such as the air-pipes, ladder, signaling devices, &c., as well as the flooring and doors of the compartments.

The structure described may be employed for building stone and concrete dams across

a river, which may be effected by employing a plurality of the structures arranged side by side with the space between each filled with concrete or the like, the filling between the structures being positioned either before or after the upper part of the dam is completed.

Having thus fully described my invention, 50 what I claim as new, and desire to secure by Letters Patent, is—

1. A caisson comprising a casing composed of spacing-beams, an inner and outer shell secured to said beams, a cement filling between 55 the shells, braces, and tie-rods provided with adjusting means.

2. A structure of the character specified having a flexible apron associated with its lower end. 60

3. A caisson comprising a casing composed of spacing-beams, an inner and outer shell secured to said beams, and a cement filling between the shells, said casing having its top closed and provided with suitable doors, and 65 a flooring below the top of the casing provided with an ingress and egress door, and a partition extending from the flooring to the top of the casing.

4. A caisson comprising a casing and having a refuse-receiving trough communicating with the exterior of the casing, a valve for precluding entrance of water to the trough, and a compressed-air-supply pipe communicating with the trough and having a valve 75 adapted to be operated to cause the air to force the contents of the trough through its discharge-opening to the exterior of the casing.

In testimony that I claim the foregoing as 80 my own I have hereto affixed my signature in the presence of two witnesses.

WILLIAM THOMPSON POOL.
